ELECTRIC FIRING MECHANISM

William E. Pollock, Greenbelt, Md.

Application August 9, 1946, Serial No. 689,354

3 Claims. (Cl. 89—28)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a new and useful improvement in electric firing mechanisms for guns using electric primers, and is designed more particularly to provide an electric firing lock for the breech block of the gun, which can be mounted in the block to replace the usual mechanical firing lock, without modification of the block. The particularly novel and useful feature of my improved device is the combination of electric means for projecting an electric firing pin forwardly from the lock through the block to contact the primer, and to energize the pin to fire the primer, and spring means for retracting the pin, said means operative to project the pin and retract the pin when the block is in battery and in recoil, respectively. This combination is effected by a single resilient member which serves as an electrical conductor to the projecting means and the pin, and also to bias the pin rearwardly in the block. The device is also provided with means to prevent arcing when the electric circuit is opened on recoil.

In the drawings:

Fig. 1 is a fragmentary top plan view of a gun equipped with my improved firing lock, the gun being in battery.

Fig. 2 is a fragmentary side elevation of parts shown in Fig. 1.

Fig. 3 is an enlarged fragmentary section partly in elevation, on the line 3—3 of Fig. 1, in the direction of the arrows.

Fig. 4 is an enlarged fragmentary section partly in elevation, on the line 4—4 of Fig. 1, in the direction of the arrows.

Fig. 5 is a greatly enlarged section on the line 5—5 of Fig. 3, with a fragment of the round in elevation.

Fig. 6 is a reduced transverse section on the line 6—6 of Fig. 5, in the direction of the arrows.

Fig. 7 is a reduced transverse section on the line 7—7 of Fig. 5, in the direction of the arrows.

Fig. 8 is a wiring diagram showing the electrical circuits.

As shown in the drawing, the gun cradle 1 has the recoil guide 2 with key-way 3 for a key (not shown) on breech-ring 4 to prevent relative rotation of the gun and mount on recoil, ring 4 sliding horizontally in guide 2. Vertically reciprocable in ring 4 is the breech block 5 in which is axially disposed the cylindrical firing case 6

(Figs. 3-4). The above described elements are standard and have been shown merely to illustrate the use and operation of my improved firing lock. Case 6 is received in an axial bore of block 5 and locked therein by keys 7 in the usual way. Case 6 contains a solenoid having its coil 8 snugly fixed into casing 6 coaxially and its core 9 slidable axially of casing 6 and having an axial bore 10 therethrough in which is disposed a tubular bushing 11 composed of electric insulation material. The rear end of bore 10 is enlarged and closed by a nut 12 threaded into bore 10 and having an axial bore 13 therethrough in which is a bushing 14 of the same material as bushing 11. The forward end of the enlarged portion of bore 10 forms a shoulder 15 against which is seated flange 16 on bushing 11. A flange 17 on bushing 14 is seated against nut 12 and spaced rearwardly from flange 16. Snugly fitted between flanges 16 and 17, there is a collar 18 on a rod 19 received in bushings 11 and 14. The periphery of collar 18 is spaced from core 9. The forward end of core 9 is recessed to form a frusto-conical face 9—a. A bushing 20 of the same diameter as core 9 is disposed in the forward end of coil 8 and has a rearwardly extending frusto-conical face 21, corresponding with face 9—a of core 9, and normally spaced forwardly thereof. Bushing 20 has a reduced forward portion 22 forming a shoulder 23 seated against the inner face of the forward end wall 24 of casing 6. Portion 22 extends forwardly through and beyond wall 24 and has threaded thereon nut 25 bearing against wall 24 to lock bushing 20 in place. Mounted in bushing 20 there is a co-axial bushing 26 of the same material as bushings 11 and 14. Bushing 26 extends rearwardly slightly beyond the rear end 21 of bushing 20, and forwardly beyond nut 25. Its forward extension 27 is received in a bore 28 in block 5 opening through the front face 29 of block 5. A suitable metallic liner 30 is mounted in bushing 26. The rod 19 extends forwardly from core 9, slidably received in liner 30, and projecting forwardly of extension 27 of bushing 26 into bore 28. Rod 19 is provided on its forward end with an electric contact firing pin 31.

The casing 6 is provided with an interior peripheral shoulder 32 registering radially with the rear end of coil 8, against which is seated a collar 33 through which is passed an insulated contact post 34 connected to one end of coil 8. The casing 6 is suitably transversely slotted to receive therein segmental blocks 35 and 36 their chords being parallel and symmetrically disposed on opposite sides of the axis of casing 6 (Fig. 6).

These blocks 35 and 36 are composed of the same material as bushings 11, 14 and 26. Collar 33 is suitably grooved to receive the forward faces of blocks 35 and 36 therein to lock collar 33 in position. A quadrilateral block 37 is disposed between blocks 35 and 36, its convex arcuate sides 38 and 39 being received against the inner surface of casing 6 and its plane sides 40 and 41 against blocks 35 and 36, respectively. Block 37 has a rectangular centrally disposed cavity 42. The rear end of casing 6 is closed by a plug 6—a threaded therein which when set up in casing 6 bears against the rear face of block 37 seating it against collar 33. Bushing 14 extends rearwardly from nut 12, slideable through block 37, into cavity 42 thereof. Rod 19 extends rearwardly beyond the rear end of bushing 14 into cavity 42 and has mounted thereon a leaf spring 43 by washers 44 and nut 45. The spring 43 has its end 46 bearing against plate 47 mounted in block 36, extending into a cavity 48 in block 36 and connected to contact post 34 which extends from coil 8, through collar 33 into cavity 48. The spring 43 has its end 49 bearing against a plane contact surface 50, in cavity 51 of block 35, of contact post 52 housed in block 35. Cavities 48 and 51 in blocks 36 and 35, respectively, communicate with cavity 42 of block 37, from which spring 43 extends its ends 46 and 49 into the cavities 48 and 51. The contact post 52 is connected to an insulated wire 53 passing out of block 35 and through a suitable conduit 54 in breech block 5 to a cam contact plate 55 mounted on the top of breech block 5 and suitably insulated therefrom.

The recoil guide 2 has an upstanding ear 56 having a lateral flange 57 disposed above the outer edges of breech ring 4. Suitably bolted on flange 57, there is a bracket 58 extending rearwardly over ring 4 on which is bolted a housing 59 disposed above cam contact plate 55 on breech block 5. Depending from housing 59 there is a cylindrical casing 60 in which is slideable vertically a rod 61 having on its lower end, exterior to casing 60, a contact head 62 for co-action with cam contact plate 55. The rod 61 is suitably insulated from housing 59 and casing 60 and has on its upper end projected into casing 59 a contact head 63. Rod 61 has collars 64 and 65 co-acting with the bottom walls of housing 59 and casing 60, through which rod 61 passes, to limit the downward movement of rod 61. Suitably mounted in housing 59, there is a leaf spring 66 urging a contact head 67 downwardly into contact with head 63 on rod 61, and a second contact head 68 into contact with a contact head 69 supported on a bracket 70 resiliently mounted in housing 59 and urged into normal position by a leaf spring 71. Spring 66 and bracket 70 are mounted in an insulated block 72 in housing 59 and bracket 70 is connected to an insulated electric conductor 73 which passes from housing 59 through conduit 74, and is connected to a source of electrical energy such as a battery 75.

It will be understood, therefore, from the foregoing description of the structural elements, that the battery 75 has one side connected with one end of coil 8 and with firing pin 31, and that these connections are insulated from the gun, its breech ring 4 and breech block 5. The other side of the battery 75 is connected by wire 76 to the usual firing switch 77 which is connected to wire 78 passed through conduit 74 into housing 59 and properly grounded on the gun to effect electric connection to the other end of the

coil 8, and through tube 79 of the gun to the proper contact members (not shown) of the round 80. It will be obvious, from Fig. 8 that, when switch 77 is closed, the circuit is completed through battery 75, the coil 8 is energized, the solenoid moves the firing pin 31 forwardly to contact the round 80, as shown in dotted lines in Fig. 5, to close the circuit through the firing mechanism of round 80.

From the foregoing description of my improved firing lock, its use and operation will be obvious. When the round 80 is in tube 79 of the gun and breech block 5 in battery, the cam contact plate 55 bears against contact head 62 (Fig. 2). It will be noted that the parts are so designed and related that the head 62 is contacted by the rear end of plate 55 which is the low portion of the cam surface. While this contact is sufficient to slightly raise rod 61 against force of spring 66 to effect a pressed contact of plate 55 and head 62, it is insufficient to lift spring 66 to move contact head 68 from contact head 69. The connection from the firing lock to battery 75 is therefore maintained closed, and the gun is conditioned for firing. When the firing switch 77 is closed, completing the circuit to the solenoid, the coil 8 is energized by battery 75 and moves the core 9 forwardly, the nut 12 bearing against flange 17 which bears against collar 18 to move rod 19 with core 9 against the force of spring 43 bearing on plates 47 and 50. The core 9 is moved to close the space between it and core 28, such movement being sufficient to cause rod 19 to project pin 31 out of bore 28 in block 5, and into contact with round 80 (Fig. 5). By the functioning of the usual electrical firing mechanism in round 80, the round 80 is fired when the pin 31 contacting round 80 closes the circuit, as above described. The recoil of the gun, on firing, slides ring 4 rearwardly along guide 2, carrying block 5, thereby moving cam contact plate 55 under head 62, bringing the forward, high portion to bear on head 62 to raise rod 61 sufficiently to lift spring 66 to move head 68 away from head 69 to open the circuit, the break being made within the closed housing 59, to prevent exposed arcing when cam contact plate 55 is moved away from contact 62.

It is obvious that the rearward movement of block 5 on recoil is sufficient to move the cam contact plate 55 clear of contact head 62, and spring 66 then functions to close the contacts 64, 67, 68 and 69.

When the solenoid is de-energized, by opening of the circuit, the spring 43, which was tensioned by the action of the solenoid moving rod 19 forwardly, now retracts rod 19 and withdraws firing pin 31 into bore 28 of block 5. On this retraction of rod 19, its collar 18 bears against flange 17 which bears against nut 12 which moves the core 9 rearwardly with rod 19, and the parts are thus restored to normal position. It will be noted that when block 5 moves downwardly in ring 4, on counter-recoil, its forward face 29 moving across the base of the case, any contact of pin 31 with the base is prevented, by the retraction of pin 31 into bore 25 of block 5. Also, it will be noted that the descent of block 5, into loading position, moves cam contact plate 55 a considerable distance, to maintain the circuit open during loading, the cam-contact plate 55 not functioning to make connection until the gun is loaded and block 5 returned to battery.

Having described my invention, what I claim is:

1. In an electric firing lock comprising the

breech block of a gun for firing a projectile having an electric primer, the combination of a firing pin slideable in said block; a solenoid in said block for sliding said pin forwardly out of said block into firing contact position; and a resilient electric conductor in said block, mechanically connected with said pin for biasing said pin rearwardly, and electrically connecting said solenoid and said pin, in parallel, with a source of electrical energy.

2. In an electric firing lock comprising the breech block of a gun for firing a projectile having an electric primer, the combination of a firing pin slideable in said block; a solenoid in said block for sliding said pin forwardly out of said block into firing position; and a spring mounted in said block, for biasing said pin rearwardly, said spring being electrically connected to a source of electric energy and to said solenoid and to said pin, in parallel.

3. In an electric firing lock for a breech block of a gun for firing a projectile having an electric primer, the combination of a casing removably mounted in said block; a solenoid comprising a coil mounted in said casing and a core slideable axially in said casing; a metallic rod mounted in said core and insulated electrically therefrom; a firing pin formed on one end of said rod, projecting out of the forward end of said casing; a metallic leaf spring on the other end of said rod; an electric contact plate mounted in said

5 casing and electrically connected with one end of said coil; and an electrical conductor mounted in said casing, said spring having its ends bearing against said plate and said conductor in electrical contact therewith, respectively, to bias said rod rearwardly in said casing, the said plate, conductor, spring and rod being insulated electrically from said casing, and the other end of said coil being electrically connected to said casing, the 10 solenoid when energized moving said rod forwardly to project said pin out of said block into firing contact position said conductor, casing and primer being connected to a source of electrical energy.
